UNITED STATES PATENT OFFICE.

VICTOR KRASKE, OF KALAMAZOO, MICHIGAN.

BANJO.

Application filed October 8, 1921. Serial No. 506,394.

To all whom it may concern:

Be it known that I, VICTOR KRASKE, a citizen of the United States of America, and a resident of Kalamazoo, county of Kalamazoo, and State of Michigan, have invented a new and useful Improvement in Banjos, of which the following is a specification.

This invention relates to musical instruments of the general character of banjos and more particularly to banjos of the type represented by the drawings.

The main objects of this invention are to provide an improved construction for the banjo as a whole, and more particularly to provide an improved form of means for tensioning the head of the instrument; to provide amplifying means of the nature of a resonator disposed in front of the brace bar and back of the head in spaced relation to the latter and with an air chamber interposed; to provide an improved form of seat or bearing ring for the calfskin head; to provide an improved form of connection for the rim and neck of the banjo; to provide an improved form of brace bar connection with radially adjustable compression means thereon to set the neck member and especially the heel part tightly against the rim; to provide an improved form of tension means connection at the heel of the neck member; to provide means for reinforcing and supporting the fingerboard extension which projects over the face of the head; to provide a banjo adapted for a wide range of musical effects and especially adapted for jazz music.

An illustrative embodiment of this invention is shown in the accompanying drawings in which—

40 Figure 1 is a plan of the instrument lying with its face side up.

Figure 2 is a front elevation of said instrument showing an edgewise view.

45 Figure 3 is a greatly enlarged section on the line 3—3 of the Figure 1.

Figure 4 is a slightly enlarged view of the back side of the head.

Figure 5 is a face view of the bearing plate of the cam lock for the brace bar.

50 In the construction shown in the drawings the instrument includes a drumhead 1 stretched on the rim 2 which is secured to a neck member 3 in substantially the same general relation as usual in such devices, though the structural details in many respects are novel, and the connecting means

embody important features of improvement.

Referring to Figure 3, the rim 2 is of nearly cylindrical shape. On its front edge is provided a celluloid bearing band 4 of 60 substantially flat shape whereon the skin of the head 1 rests, with a lengthwise bend to fit the rounded corner of said rim. This band is formed with the grain disposed lengthwise or circumferentially and is 65 adapted to provide a smooth and secure bearing surface which will not cut or injure the head. This is regarded as an important feature.

Adjacent to the flat band 4 and disposed 70 outwardly and embracing the front edge of rim 2 is a straining hoop 5 having an angular cross section. This hoop is made of metal and is provided with a corner groove 6 to receive the flesh wire 7 about which the 75 edge 1' of the head skin is folded. One side of said hoop is cylindrical, as shown at 5', and fits snugly against the backwardly turned part of the head and the other part 5'' extends outwardly in a plane at a right 80 angle to part 5' to receive the tension bolts 8 which serve to pull the hoop 5 rearwardly toward the tension ring 9 adjacent to the opposite edge of the rim 2. Said ring 9 is 85 rigid with said rim 2.

In order to amplify the sound and give the required character thereto in accordance with specific requirements desired, a resonator in the form of a wooden partition or diaphragm 10 is provided in front of the 90 brace bar 18 and back of the drum head 1 with an amplifying chamber 11 intervening. Said resonator may be made of wood to produce soft sounds and of metal to produce the harder sounds, and is provided 95 with a sound hole 12 preferably located one third across from the outer edge. The rim 2 is provided on its inner side with an annular shoulder 13 facing toward the front whereon said resonator is seated, the latter 100 being secured in place by a resilient expansion ring or locking hoop 14 which may be secured in any desired manner as by wood screws 15.

The neck 3 is rigidly secured detachably 105 to the rim 2 as will be described. Said neck is thickened adjacent to the rim as shown at 16 to provide a shoulder-like bearing or heel which fits against and entirely across the outer side of rim 2. Said neck 110 is somewhat fork-shaped at this point and is provided with a fingerboard extension

which projects over the drum-head as shown at 17, and with a brace bar 18 or taper post as it is sometimes called which projects through a perforation 19 in rim 2 and extends diametrically across the rim back of the resonator 10. The tip of said brace bar fits snugly in an aperture 20 in the opposite face of rim 2 whereby the brace bar may be effective to rigidly support said rim.

10 In order to provide for ready assemblage and taking apart of the rim and neck, a manual lock is provided at the inner end of bar 18. For this purpose the bar 18 is provided with a longitudinal slot 21, wherein is mounted a cam disk 22 arranged to react forcibly against the inner face of rim 2. Said cam disk is mounted on a pivot 23 set in bar 18, and a metal bearing plate 24 is provided to fit against said rim, said plate comprising a shank 24' to fit in said slot 21, and a head 24'' having shoulders 24''' to seat against the outer face of said bar. Said plate is removable to permit withdrawal of the bar 18 for removal of the neck 3. Said cam disk is provided with radial holes 25 to receive a wrench or key, not shown. When the cam is turned in one direction it bears wedgingly against the plate 24 and so forces the brace bar inwardly 20 and locks the same rigidly in place.

In order to offset the pull of the strings 27, a tension rod 28 is provided as shown in Figure 3, which rod because of its function, I call a coordinator. The inner end of said rod is threaded to fit a nut 29, which is set rigidly and permanently in the base of neck 3. Said rod 28 also passes through the hole 24' in plate 24 which is clamped by a nut 30, and the opposite end of said rod is also provided with nuts 31 and 32 which clamp against the inner and outer side respectively of rim 2. The nut 29 has a tubular projection 29' which is enclosed in a wooden sleeve or bushing 26. Said nut and bushing fit snugly in the hole 16' of heel 16 where they are set in glue or cement.

The heel of the neck 3 is apertured and formed to accommodate the necessary adjusting movement of the straining hoop 5 as shown at 33. The flange 5'' at this point is narrowed somewhat so as to minimize the size of aperture in neck 3. Moreover the cylindrical part 5' of the stretcher band is apertured at its outer edge as shown at 55 85 in registry with the overlapping projection 17 of the fingerboard so as to provide a sufficient range of adjustment of band 5 without making the fingerboard extension too thin or weak.

60 Another feature of this invention is the built-up or reinforced construction of the fingerboard extension 17. The finger board is faced with a veneer strip 36 of ebony or the like which extends continuously from 65 end to end, whereon the frets 37 are

mounted. The projecting part of said strip 36 which extends over the drum-head is supported on a reinforcing plate 38, the inner end of which is seated in an aperture 39 of the neck base. Said plate is cemented 70 both to the neck and to the first supporting strip 36.

A bridge 40 is provided as usual for the strings 27 and rests against the drum-head 1, said bridge being adjacent to the edge of the 75 rim where the strings 27 are attached. Moreover, a pair of bridges 41 are held in compression between the drum-head 1 and resonator 10 preferably adjacent to the side of the rim 2 where secured to the neck 80 base or heel 16.

The strings 27 are secured to the straining hoop 5 by means of pins 42 set in the flange 5' and perforations 43 through the flange 5'', said strings being wound once 85 about their pins respectively and threaded through their holes 43, and then being knotted as shown at 44. The tension bolts 8 are each provided with a head 8' to bear against the front face of flange 5'' and a 90 nut 8'' to bear against the ring shoulder 9'. Said nuts may be operated partly with the thumb and finger, but for setting tightly a wrench, not shown, is used.

Although but one specific embodiment of 95 this invention has been herein shown and described it will be understood that numerous details of the construction shown may be altered or omitted without departing from the spirit of this invention as defined by the following claims.

I claim:

1. In an instrument of the character described, a drumhead and rim, in combination with a resonator board disposed in said rim adjacent to but spaced somewhat from its front edge, said rim having an annular shoulder against which said board is seated at its edge, a resilient expansion ring disposed against the outer face of said board opposite said shoulder to lock said board in place demountably and means to secure said ring in place.

2. A stringed instrument of the character described comprising a drumhead, a rim whereon said drumhead is stretched, a laterally projecting neck member secured to said rim, said neck member having a brace bar unitary therewith, a resonator disk disposed in front of said bar in spaced relation thereto, whereby said disk is free to vibrate, strings for vibrating said head, and bridge means disposed effectively between said head and disk to transmit vibrations to the latter from said head.

3. An instrument of the character described comprising a drumhead, a rim therefor provided with means for tensioning said drumhead and vibratile strings, said tensioning means including a straining hook of 130

angular cross-section adapted to embrace the front edge of said rim with the edge of the drumhead interposed, and a plurality of tension bolts, said rim having a perforated 5 tension ring of shouldered character rigid with the outer face thereof, the outstanding flange part of said hoop being disposed toward the back and away from the front or drumhead side of said instrument and perforated in registry with perforations in said ring to receive said bolts, and said hoop having pins in its forwardly disposed cylindrical part to receive said strings.

4. In a banjo, a rim in combination with a 10 neck having a brace bar extending through and across said rim in combination with a

manually operable cam to pull said bar tightly into said rim and adapted to lock the same in place.

5. In a banjo having a neck, rim and brace bar, a tension member provided with readily detachable connecting means for engaging said neck and rim back of said bar, said means including a nut having a cylindrical shank, and a sleeve fitting thereon, 20 said neck having an aperture to receive said nut and sleeve wherein they are secured permanently by cement or the like.

Signed at Chicago this 5th day of October, 1921.

VICTOR KRASKE.
